UNITED STATES PATENT OFFICE.

JOHN B. BURWELL, OF STAUNTON, VIRGINIA.

WRITING-TABLET.

SPECIFICATION forming part of Letters Patent No. 239,296, dated March 22, 1881.

Application filed February 8, 1881. (No model.)

To all whom it may concern:

Be it known that I, JOHN B. BURWELL, a citizen of the United States, residing at Staunton, in the county of Augusta and State of Virginia, have invented certain new and useful Improvements in Writing-Tablets; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to that class of writing-tablets or memorandum-blocks which are composed of a number of sheets of paper suitably secured together, and capable of being readily separated when used.

20 It has been proposed to provide tablets of the above description with an outer leaf or cover composed of absorbent or blotting paper, which serves to remove the surplus ink from the written sheet. It has been found that such an outer leaf of absorbent paper will not remain in a perfect condition until the sheets of paper are exhausted, because, by reason of its exposed or unprotected position, it is liable to get torn or bent, particularly

25 30 when the tablet is carried in a pocket or is thrown about.

The present invention obviates the defects of such a tablet having an absorbent outer leaf, and is also designed to furnish a tablet which is more satisfactory and capable of a more extended use. I attain these results by constructing a tablet of a central sheet of card-board or other stiff material, and attaching thereto, by flexible strips, two outer covers of card-board, to the inner sides of which are secured sheets of blotting or absorbent paper. The sheets or leaves of paper to be written upon are held together at their upper edges by cementing or otherwise securing them to the flexible strips which form the hinge-joints of the outer covers. The central or division board extends beyond the upper edge of the tablet, and has an eyelet therein for suspending the tablet when not in use.

In the drawings, Figure 1 is a perspective view, showing one of the covers thrown up. Fig. 2 is a longitudinal section.

The letter A designates a central sheet of card-board or other rigid material, which serves as a division board or strip, and projects beyond the upper edge of the body of the tablet, as is shown at B. A number of sheets of paper, C, secured together at their upper edges, constitute the tablet proper, and are located or arranged on both sides of the division board or strip A. In this manner I produce a double tablet, which is capable of being used when either side is up.

The letter D designates two outer covers, made of sheets of card-board or other suitable rigid material, and attached to the division-board A by means of flexible strips E, of textile fabric or leather. To the inner side of each cover, or to the flexible strips forming the hinges, I attach, by cement or otherwise, a sheet of blotting or absorbent paper, F. These blotters are only attached at their upper edges, as is also the case with the sheets of paper to be written upon. The projecting portion of the division-board A is made narrower than the rest, and has an opening or eyelet, G, at its upper end, for the purpose of hanging the same from a hook or peg. Any other suspension device may, however, be used in place of the eyelet.

It will be obvious that a double or reversible tablet constructed in the manner above set forth is capable of a more varied or extended use than a single tablet. Moreover, effectual means are provided for protecting the blotters from being torn or broken, and consequently the soiling of the sheets of paper is also prevented.

It will be understood that the sheets of paper may have any printed matter upon the same, as in the tablets in common use. I preferably print a calendar upon the central card or division-board, and the outer covers may bear any desired advertisements.

I disclaim a writing-tablet having an outer sheet of blotting-paper, and restrict myself to the precise construction herein shown, or, in other words, to a tablet or book which has

outer protecting-covers, and is capable of being opened from either side, thus avoiding the trouble of turning the tablet right side up.

What I claim as new, and desire to secure 5 by Letters Patent, is—

A double or reversible writing-tablet, composed of a central division board or card having a projecting upper end, the rigid outer covers, and the sheets of blotting and writing

paper arranged between said outer covers and to the division-board on both sides of the latter, as and for the purpose set forth.

In testimony whereof I affix my signature in presence of two witnesses.

JOHN B. BURWELL.
